METHOD FOR TREATING POURING ORIFICES FOR DRIP-FREE CONTAINERS

Robert E. Ford, Minneapolis, Minn., assignor to Luther Ford & Company, a co-partnership, composed of Allyn K. Ford and Robert E. Ford, Minneapolis, Minn.

Application July 15, 1933, Serial No. 680,598

7 Claims. (Cl. 91—70)

My invention relates to drip-free containers and the method and apparatus for treating pouring orifices thereof. It is the object of my invention to provide pouring orifices of containers from which liquids are to be poured such as bottles, pitchers, cans and the like, with a substance which will not have any capillary affinity for the liquid to be poured, the result being that when the container is restored to containing position the surface tension of the liquid going back into the container will be greater than any tendency of the liquid to cling to the surface of the orifices, with the result that liquid on the rim of the bottle neck will be drawn back over said surface and return to the container and none of it will drip from any part of the orifice. Stated in another way, the prepared surface will be of such a nature that no part of the liquid being used will cling thereto, as, if water were all or any considerable part of the liquid, the surface would not be wet thereby.

It is a further object of my invention to produce containers such as bottles, pitchers, cans and the like adapted for the holding of liquid to be poured therefrom, and having the pouring orifice such as the lip surrounding the neck of a bottle, the rim of a can, or the spout of a pitcher treated with a material such as wax or paraffin or any suitable composition so that a layer thereof will be adherent to the exposed parts of the pouring orifice and will have the effect of repelling the liquid so that the surface tension thereof may draw all of said liquid back into the container when it is erect and no part thereof drip therefrom.

It is a further object of my invention to provide a process for applying said liquid-repellant material to the top edge and rim of said containers in such manner that when the liquid is poured therefrom and the vessel is reverted to erect position, the film of such material will be so placed as to prevent dripping, as above stated, and to employ a process which will provide such a film thin enough so it will remain on the bottle and outside of the interior of the neck of the bottle so it will not be destroyed by the cork.

Difficulties are encountered in the provision of such a film for the reason that there is a tendency for the film to form on the inside of the bottle as well as on the top edge and over the edge of the rim, there is a tendency for the material to solidify and form globules or drops on the top edge which will be easily knocked off, and there is a tendency for the film to form too thick, which likewise results in its easy destruction.

It is the object of my invention of process to provide steps for eliminating these undesirable results, and I accomplish this by the steps of process which consists in providing a suitable receptacle and melting and heating the liquid-repellant material therein, preliminarily heating the neck of the bottle or the surrounding portions of the orifice either by introducing it into the heated liquid-repellant material and there retaining it until the temperature of the edges of the orifice and adjacent surfaces are heated to a temperature above the melting point of the liquid-repellant material, or by providing a heated surface and placing the edges surrounding said orifice in contact with said heated surface until the temperature of adjacent portions thereof is raised above the temperature of the liquid-repellant material, and thereafter introducing the same into the melted material. This will cause a film of the liquid-repellant material to adhere to the edges and surfaces outside and adjacent the orifice and at the same time because the air in the bottle is being heated and will thereby be caused to expand and will push out at the edges of the orifice, repelling the melted material and preventing it from entering the orifice. Thereafter I withdraw said edges from the melted material and either wipe away part or all excess melted material from the edges or hold the containers in position until such excess material is drained off. I then withdraw the container to a position usually upright, where the exceedingly thin film of liquid-repellant material remaining will harden and become firmly attached to the container.

It is a further object of my invention to provide forms of apparatus for carrying out the steps of my process. While this apparatus is shown specifically applicable to containers such as bottles, it will be understood that the principles of operation of the apparatus will apply to other forms of containers such as pitchers or cans.

Other objects and advantages of my invention will appear in connection with the detailed description thereof and the novel features of my invention are particularly pointed out in the claims.

In the drawings, illustrating a construction of my invention and apparatus for carrying out the process,—

Fig. 1 is an elevation view of part of a bottle having my invention applied thereto. Fig. 2 is a sectional elevation of the neck of the bottle shown in Fig. 1. Fig. 3 is a longitudinal part sectional view of a form of the apparatus for carrying out

my invention taken on line 3—3 of Fig. 4. Fig. 4 is a plan view of the apparatus shown in Fig. 3. Fig. 4a is a fragmentary plan view of the vertical intermittent bottle shifter showing a modified carrier construction. Fig. 4b is a fragmentary elevation view of a portion of said carrier to show the same construction. Fig. 5 is a sectional elevation view on line 5—5 of Fig. 4. Fig. 6 is a sectional elevation view on line 6—6 of Fig. 4. 10 Fig. 7 is a sectional elevation view on line 7—7 of Fig. 4. Fig. 8 is a sectional elevation view on line 8—8 of Fig. 4. Fig. 9 is a sectional elevation view taken on line 9—9 of Fig. 4. Fig. 10 is a sectional plan view taken on line 10—10 of Fig. 9. Fig. 11 15 is a sectional elevation view on line 11—11 of Fig. 9. Fig. 12 is a sectional elevation view of another form of apparatus for carrying out my process taken on line 12—12 of Fig. 13. Fig. 13 is a part sectional plan view taken on line 13—13 20 of Fig. 12. Fig. 14 is a sectional elevation view on an enlarged scale taken on line 14—14 of Fig. 13. Fig. 15 is a part sectional elevation view of another form of apparatus for carrying out the 25 steps of my process. Fig. 16 is a sectional plan view of a portion of the apparatus shown in Fig. 15 with the bottle containing carton removed. Fig. 17 is a fragmentary elevation view of the upper right-hand corner of what is shown in Fig. 15. Fig. 18 is a sectional elevation view of the 30 upper part of the apparatus shown in Fig. 15 taken at right angles to the parts as shown there. Fig. 19 is a sectional elevation view showing the manner of applying the bottle dipping holder to a carton of bottles. Fig. 20 is a top plan view 35 of what is shown in Fig. 19. Fig. 21 is a sectional view of what is shown in Fig. 19 with all parts inverted. Fig. 22 is a fragmentary view of a portion of a bottle-holding carton showing the bottles positioned in individual compartments.

40 As shown in Figs. 1 and 2, the upper part 10 of the neck of a bottle 11 has applied thereto a coating 12 of some material adapted to repel the liquid to be contained in the bottle and to be poured therefrom, as, for example, liquid bluing, in 45 which case the layer 12 will consist of water-repellant material such as a firm grade of paraffin wax. The layer of said paraffin wax will lie upon the top of the expanded neck portion 13 of the bottle as at 14, and will extend a short distance down about the inside of the neck of the bottle, as at 15.

Such a layer of liquid-repellant material must be firm, must cover the pouring surface completely, must be thin, and must be applied so as 55 to remain adherent under all normal conditions of handling and use. For this layer I have employed different forms of paraffins, of which those with the highest melting points are preferable, beeswax, canauba wax, and combinations 60 of the above. For use where the liquid is water or water solutions the highest melting point paraffin wax has been found effective and satisfactory.

The process of applying such a layer consists 65 in heating the wax or other material to a desired temperature, preliminarily heating the neck of the bottle to cause the air to expand and be expelled around the mouth of the bottle, inserting the part of the bottle to be coated, either preliminarily heated or not as desired, into said heated wax and maintaining the temperature of said heated wax, retaining the portion of the bottle so submerged within said heated wax for a sufficient duration of time to heat said portion 70 to substantially the temperature of the heated

wax, withdrawing the part to be coated from the wax, and removing excess wax from said part by holding the bottle in such position that full drainage is possible or by wiping the coated part of the bottle on a hot surface, or both, whereby a thin film will be produced. 5

Figs. 3 to 11, inclusive, show a form of apparatus for automatically and rapidly performing the above steps to effect the desired application of said film. 10

In this machine there are two rotating carriers, one, 16, being mounted on a horizontal shaft 17 supported upon frame legs 18 and 19, said shaft having bearings 20 and 21 in transverse frame pieces 22 and 23. The second carrier comprises a horizontal rotatable table 24 of a semiconical shape as indicated at 25 in Fig. 7, which is provided with a surrounding gear 26 and is journaled on a thrust bearing 27 held in a casting 28 for vertical adjustment by means of a threaded hand nut 29, whereby the table 24 may be raised or lowered as desired. The casting 28 is secured to a transverse frame piece 30 by means of a bolt 31 upon which the same is pivoted and a bolt 32 passing through an oblong slot 33 in an ear 34 on casting 28. By means of a setbolt 35 in Fig. 7 the casting piece 28 may be rocked upon pivoted bolt 31 more or less to place the table 24 more or less at an angle to the vertical for a purpose hereinafter to be stated. 30

The casting 28 is provided with a table 36 upon which is supported an annular trough member 37 formed above a mass of insulating material 38. The trough member 37 is adapted to hold the wax or other material as indicated at 39 which is kept in a properly fluid and heated condition by means of electrical heating elements 40 served by wires 41. The trough member 37 has secured thereto an annular wall 43 to which is secured in spaced relation a second annular wall 44, being held in position by washer nuts 45, said walls 43 and 44 forming an annular passage 42 as clearly shown in Figs. 3 and 7. And this carrier will, by reason of its contact with the heads of the bottles, and when the annular channel or passageway 42 is 45 filled with bottles, as shown in Fig. 10, move the bottles uniformly along said channel at the speed at which the carrier 24 rotates. If the table is horizontal in position, and with heated wax at a level above the projecting rings on the bottles 50 46, these portions of the bottles will dip within the melted wax for the entire period of a revolution of the carrier 24, as appears from an inspection of Fig. 7. In some cases, however, it is desirable to keep the bottles in the wax only part 55 of the time, in which case by means hereinbefore described, the carrier and table may be tilted and the bottles then will dip into the wax at one side only and preliminarily heat and drain at the other side. 60

As clearly appears from Fig. 7, the carrier 16 embodies a multiplicity of pockets 47 each adapted to hold one of the bottles 46, and the carrier 16 moves the bottles 46 in a vertical plane across the channel 42 and above the carrier 24 operative 65 in a horizontal plane. Referring to Fig. 10, two chutes enter the channel 42 from opposite sides to admit the introduction into said channel of a bottle by carrier 16 and the simultaneous withdrawal of a treated bottle on the other side. The 70 introduction chute 48 is formed by wing plates 49 and 50, and the withdrawal chute 51 is formed by wing plates 52 and 53.

Referring to Fig. 3, it will be noted that the width of the top surface 54 of the carrier 16, and 75

also the widths of the plates 55 forming the pockets 47 is only a little more than one-half as great as the transverse dimension of the bottles to be handled. Also, that the guide plates 49 and 50 at 5 one side and 52 and 53 at the other side of the channel 42 (Figs. 4 and 10) are separated the same distances, sufficient comfortably to receive a bottle across one of its dimensions, but that these plates do not lie in the same vertical planes 10 but plate 49 outside of the channel 42 is positioned close to one side of the vertical plane of carrier 16 and plate 52 inside of a vertical extension of channel 42 is positioned close to the other vertical limit of carrier 16. For this reason 15 bottles moved by carrier 16 are displaced laterally with respect to one another, as clearly indicated by full-line bottle designated 56 and dotted-line bottle designated 57 in Fig. 3.

A guideway formed by side rails 58 and 59 has 20 at its bottom supporting plates 60 and 61 separated at 62 with a plate 63 bridging the gap there. An endless conveyor 64 runs over the plate 61 and forms the bottom of the guideway at that point, and a second endless conveyor 65 overlies 25 plate 60 and discharges upon a receiving plate 66 at its front end immediately in front of the carrier 16, as clearly shown in Figs. 3 and 4.

Power for driving the various instrumentalities 30 is furnished by motor 67 transmitted through belt and pulley arrangement 68 to gear box 69 which operates drive shaft 70, and a cam wheel 71 at one end thereof carrying a cam actuator 72 adapted to engage in slots 73 of a star wheel 74 mounted on shaft 17, which also has on it the 35 carrier 16, which arrangement gives said carrier an intermittent step-by-step rotary motion in a vertical plane. The other end of said shaft 70 has thereon a spur gear 75 adapted to mesh with change speed gearing 76 on a shaft 77. Through 40 bevel gearing 78 and spur gears 79, 80 the belt conveyors 64 and 65 are driven at different speeds, conveyor 64 being driven more rapidly than the conveyor 65, whereby bottles loosely stacked in the runway above conveyor 64 will be pushed forward and caused to contact in fixed relation above conveyor 65.

From shaft 77 there is driven by means of bevel gearing 81 a vertical shaft 82 supported by 50 a thrust bearing on a bracket 83 and adapted to be lifted vertically for a purpose hereinafter to be described. Upon the lower end of shaft 82 is a spur gear 84 adapted when in its lower position to mesh with the gear 26 on the horizontal carrier 24, as shown in Figs. 9 and 11. When in operative position the spur gear 84 will be running 55 in the melted wax or other material to be applied to the bottle, as shown in Fig. 11. When the machine is out of operation the shaft 82 and the gear 84 will be lifted to take the gear out of said wax.

60 The operation of these instrumentalities will now be described. Bottles will be stacked loosely in the guideway upon conveyor 64 with the necks of the bottles erected, whereby said bottles will be caused to contact in a row above conveyor 65 and will be moved in contact from said conveyor upon plate 66. The feed of conveyor 65 is timed with the operation of the vertical carrier wheel 16, so that at each operation of carrier 16 a bottle is pushed from the plate 66 upon the 65 carrier 16 to the dotted-line position 57. At the same time the bottle 56, which has come up in a compartment 47 of carrier 16 is pushed to the dotted-line position 85 (Fig. 3), where it rests upon a supporting plate 86. At the next operation 70 the bottle in the dotted-line position 85 will

be pushed from the supporting plate 86 to a rotating delivery table 87, when it will be delivered to any suitable receiving, packing or storing mechanism.

Electric current from wires 41 in heater 40 will have brought the wax 39 in the lower trough 37 to a desired molten state and temperature. At each operation of the vertical carrier 16 bringing down through chute 48 a bottle on the carrier in the dotted-line position 57 of Fig. 3, a bottle will be introduced into the channel 42, where its head will contact with the rotating table 24 and the bottle will be withdrawn from its compartment 47 just in time with the succeeding operation of vertical carrier 16 to introduce another bottle into channel 42. This will continue until the entire channel is filled, as shown in Fig. 10. At a succeeding operation of the vertical carrier 16 the bottles in the channel 42 will have the dotted-line position shown in Fig. 20 10. That is, a bottle indicated in dotted lines at 88 will have the forward part only above the carrier top 54 at the moment of actuation of carrier 16, which will take the bottle out of channel 42 in the position on carrier 16 indicated in full lines by bottle 56 in Fig. 3. At the same time, a new bottle coming down through passageway 48 will go with this compartment 47 25 into the channel 42 and will be removed therefrom by continued rotation of the table 24. In this manner the bottles will be successively fed to the passageway 42 with their thickened neck portions just dipped into the fluid hot wax substance 39, and will remain therein (either for a full revolution or for a part of a revolution, according to the adjustment of the table as horizontal or tilted) during an entire revolution of said table 24. After the bottles have been withdrawn they will be lifted step by step to the upright position of Fig. 3, giving opportunity for melted wax to drain, and then will be discharged upon receiving table 87.

It will be noted that the table 24 has the conical surface 25 any element of which forms an arc of the circle described by the outer edges of the bottles on carrier 16, Fig. 7. This table 24 of solid metal dips into the heated material all the way around, preferably being tipped so that its uptipped portion has its surface continually out of the melted wax while the downtipped surface 50 dips beneath the surface of the melted wax at its lowest point just sufficiently to carry the rims of the bottles sufficiently dipped in the wax, in practice form one-thirtieth second to one-sixteenth of an inch. Because, however, the table 24 has 55 its outer edges at all times immersed in the hot wax, the table itself becomes heated.

As the bottles are moved about through a complete revolution on table 24, the first effect (either when the bottles pass immediately into melted wax when the table is horizontal, or when they move on the hot dry part of the table when it is tilted) is to begin to heat the bottle itself and the air within the bottle. This heating of the air has the effect of course of expanding the air, which tends to make it flow out of the neck of the bottle all around the lip thereof, and which positively holds the wax back from contacting with the inside of the neck and prevents the formation of a film of wax on the inside of the bottle where it is not desired. Throughout the entire circuit on the platform or table 24 this heating and expansion of air will continue, small bubbles of air passing out all around the inner edge of the neck of the bottle so when the bottle leaves the melted 70 75

wax it will be practically entirely free from a film of wax on the inside of the bottle. The wax forms upon the upper edge of the lip about the neck of the bottle and over the outside for a short distance, but not on the inside of the cylindrical part of the neck, which is very desirable, since it might otherwise interfere with the use of stoppers and also the film would be broken by the employment of stoppers.

10 Where table 24 is tilted the bottles will come into the plane of vertical carrier 16 partially drained on account of passing up upon a partially-dried surface. Where table 24 is horizontal the bottles will, of course, have the rim of the 15 neck still fully immersed. When the vertical carrier 16 removes the bottles the rim of the bottle continues to contact with the surface 25 of table 24, as shown in Fig. 7. Since the conical surface 25 is hot, and at this point dry, rubbing the said 20 rims in contact with such hot, dry surface removes most of the excess material or wax on the outer edge of the rim which slowly runs down said hot surface 25 until when that portion of the surface has completed another complete revolution 25 it will again be substantially dry. The bottle lifted to the position shown in Fig. 7 in contact with surface 25 remains in this draining position during the rest between steps, and is further rubbed in the next succeeding step and cools 30 during the next two rests and steps, which will bring the bottle vertical, where it is pushed off on the revolving table 87, where it is fully cooled and the wax completely hardened, the resulting film of wax being exceedingly thin and altogether outside the interior of the neck of the 35 bottle as required.

In practice it has been found that this device will operate satisfactorily as above described. To make certain that bottles will be accurately positioned for introduction into the compartments 47 from the conveyor 65, I may employ the construction shown in Figs. 4a and 4b, wherein cams 147 are provided at the sides of the container portions of the bottle-containing pockets 47 on 45 the vertical rotating carrier 16. It follows that as this cam 147 passes the bottle-holding platform 66 it will hold back the nearest adjacent bottle 46 until a pocket 47 is in position to receive a bottle, thus insuring against feeding of untreated 50 bottles off of the carrier 16 to platform 86, and insuring accurate positioning of the bottles in the several succeeding pockets, and securing against breakage.

In the form of device for applying my process illustrated in Figs. 12, 13 and 14, I employ a large wheel-like table member 90, its hub 91 supported on a thrust bearing 92 to rotate about a shaft 93 suitably supported by a pedestal 94 in such manner that the plane of the table is slightly tilted 60 from the horizontal. The outer periphery of the table 90 carries an insulated annular trough member 95 adapted to contain melted wax with a multiplicity of spaced heating elements as herein-after described. The table is rotated slowly, in 65 practice it requiring about one minute for each complete revolution. Owing to the tilt the annular carrier bar 96 for receiving the edges of the rims of the bottles will have its surface immersed in the wax for a part of said revolution, 70 in practice about one-third, and said surface will be out of the wax for the rest of the period of the revolution. All of the carrier, however, will have its body portion immersed in the heated wax and the surface will be heated to substantially 75 the temperature of the melted wax throughout

the entire circumference thereof. In consequence of this operation the surface out of the wax will be hot and in large part will be dry. The bottles placed upon this surface near the center of the dry portion will be preheated before reaching the 5 wax, thus heating the air within the bottles and starting its expulsion around the rim to prevent inflow of wax to the inside of the bottle neck. The bottles will be moved through the heated wax and then will be carried along the part of the up- 10 tilted carrier bar in a draining position for about a third of the revolution with the rim of the bottle in contact with the hot surface of the annular carrier bar. This will result in substantially 15 complete drainage before the bottle reaches the point of withdrawal, which is of course near the same point where it was put on the runway.

An advantageous feature of tilting the wheel table 90 comes from the fact that thereby the melted wax in the annular chamber or trough 95 is given a continuous wave-like current movement through said trough, whereby its temperature is maintained uniform, and there will be no hot spaces over and cold spaces between the heater elements hereinafter described. And, specifically, annular supporting band 96 is held by means of bolts 97 spaced from the walls of the trough as clearly indicated at 98 in Fig. 14, and also at each side in Fig. 12. In the bottom of the annular trough 95 are a series of heating elements 99 supplied with electricity from the lead wires 100, 101, 102, 103, 104 and 105, which wires run to annular contacts 106 on a supporting table 107, said contacts being fed with electrical current from wires 108 carried from electrical cable 109. As shown by dotted line 110, the plane of the trough 95 is at a slight angle to the horizontal, so that if liquid wax therein at one side, as indicated at 111, is even with or slightly below the top of the supporting annular band 96, the wax at the other side, as indicated at 112, will have a suitable depth for immersing the protruding part of the neck of the bottle. By means of suitable power connected with cable or belt 113 surrounding the outside of the trough member 95 the entire mechanism will be driven at a suitable speed. The operator stands in a given position, as at 114, and puts bottles into the trough at one side and withdraws them from the trough at the other side, where they may go to a bottling machine or to packing and storing facilities. The supporting band 96 everywhere overlying wax and heating elements will be very considerably heated, which will gradually heat the bottles, the neck of course being heated first.

The third method of carrying out my process simply and economically is illustrated in Figs. 15 to 22 inclusive. In this form an insulated trough 115 is supported upon a stand 116 and is adapted to hold wax or other suitable material 117 which is heated by electrical elements 118 served by wires 119. Within the trough 115 is a supporting grid 120 comprising side members 121, 122 which overlap the edges 123 and 124 of the trough or receptacle 115 and which are pivotally secured upon a rod 125 journalled in ears 126 and 127 fast on the trough member 115. By means of cross supports 128 and pairs of separated longitudinal supports 129 or pairs of contacting longitudinal supports 130, a grid is built up in position to receive the ends of bottles as they are packed and shipped in cartons, the ends of the bottles being supported upon longitudinal grid members 129, 130, as indicated in Figs. 15 and 18. As indicated in Figs. 19 and 20, bottles come in 75

cartons 131, usually two dozen in a carton, said cartons being divided into compartments 132 by means of suitable longitudinal and transverse partitions 133. I provide a cover member 134, shown in plan in Fig. 20, which has surrounding side members 135 preferably flared at the edges, as indicated at 136 and having a top 137 formed with a multiplicity of openings 138 positioned to come directly above the necks of bottles, as clearly shown in Fig. 20. The cover member 134 has handles 139 by which it is positioned and depending portions 140 extending from the ends by means of which the device is rested upon a table or platform with the bottles positioned therein. 15 In using this device the cover flaps 141 of the carton or packing case are turned down, as indicated in Fig. 19 and the cover member 134 is placed over the carton so as to rest upon the upper edges thereof, as clearly shown in Figs. 19 20 and 20, in which latter figure the upper ends of the bottle necks are visible. Both carton and cover member are then turned into the position of Fig. 21, when the bottles will gravitate down the compartments 132 and the necks thereof will 25 protrude through the openings 138, being held by the supporting members 140. In this position, by use of the handles 139, the carton and cover, with the necks of the bottles protruding, is transferred to the trough member 115. As shown in Fig. 18, 30 the leg members 140 come on each end of said trough member, the top 137 of the cover member rests upon the outer edges of the trough member and the bottle necks will be positioned upon the supports 129 and 130, where they will be just 35 immersed within the heated wax, whose level is indicated at 142. After they have been immersed for a certain length of time the grid member formed within the bars 121 and 122 is rocked upon its axis 125 by means of a foot treadle 143 40 connected by a link 144 and maintained in normal level position by a spring 145. When the carrier is rocked to the dotted-line position indicated at 146 in Fig. 15, it is retained in that position for a sufficient length of time for the surplus 45 melted wax to drain off.

In this form of apparatus for practicing my process it is necessary to maintain the wax at a hotter temperature than in the other forms, in which, particularly the large wheel trough 90, a 50 comparatively low temperature above the melting point of the wax is all that is requisite. In the last described device, all of the bottle necks being dipped in at once, there is a tendency to cool the wax and cause it to congeal about the 55 rims of the bottle necks. This is offset to some extent by the excess heat of the wax, which also instantly starts heating the air, causing it to tend to flow outwardly at the edge of the rim of the bottle on the inside and repel inflow of wax. 60 Very quickly, also, the wax which is solidified upon the bottle rims remelts. When the bottle rims have reached substantially the temperature of the wax, and the carrier is rocked to the dotted-line position 146, the bottles are held 65 angularly positioned for drainage. All of the surplus wax on the outside of the bottle rims will run around such rims to their lowest points, where it will drip away before the bottles cool sufficiently to solidify the wax. When the drainage is complete the case of bottles is removed and reverted to hold the bottles in erect position, where the very thin film of wax remaining on the rims and the outside of the rims of the bottles quickly cools and solidifies and the bottles are in 70 position for transport and use.

The advantages of my invention have been quite fully pointed out in connection with the detailed description thereof. Primarily invention resides in the discovery that if a film of material repellent to any particular liquid in a container is applied to the rim of a pouring orifice, the surface tension of the liquid will be sufficient to pull back all parts of the liquid when the container is restored from pouring to non-pouring position, with the result that there is no drippage from the pouring orifice.

The various methods of practicing my process are shown herein as applicable specifically to bottles. It is to be understood, however, that the invention applies to all forms of containers from which liquids may be poured, and to all types of liquids, and is not to be limited to bottles or to bottles adapted to contain bluing, such as are specifically shown.

I claim:

1. A process of preparing liquid containers having pouring orifices so as to render them non-dripping, which consists in melting and heating a liquid-repellant material having capability of solidifying on a surface in extremely thin and strongly adherent films, introducing the edges of the pouring orifice into said heated liquid-repellant material, retaining said edges in said liquid-repellant material until adjacent parts of the container are heated to a temperature above the melting point of said heated material, subsequently withdrawing said edges from the melted material, causing excess of said material to be removed therefrom, and cooling the material on the top and outside of said rim until it forms a hard, stable film.

2. A process of preparing bottles so as to render them non-dripping, which consists in melting and heating a liquid-repellant material having capability of solidifying on a surface in extremely thin and strongly adherent films, inverting the bottle and setting its rim upon a hot surface to preheat the rim and neck of the bottle and to heat the air therein to cause it to tend to push out around the neck of the bottle and prevent inflow of heated material, introducing the edges of the rim of the bottle into said heated liquid-repellant material, causing excess of said material to be removed therefrom, and cooling the material remaining on the top and outside of said rim until it forms a hard, stable film.

3. A process of preparing bottles so as to render them non-dripping which consists in melting and heating a liquid-repellant material having capability of solidifying on a surface in extremely thin and strongly adherent films, holding the bottles inverted against a support, heating the support so that thereby the bottle neck will be heated, and carrying the bottle on the support into and out of the hot melted material whereby expanding air within the bottle flowing out around the supported edge of the bottle-rim will prevent entrance of liquid-repellant material to the inside of the neck and a very thin film of the liquid-repellant material will be laid on the outside only of the bottle-rim and neck.

4. A process of preparing bottles so as to render them non-dripping which consists in melting and heating a liquid-repellant material having capability of solidifying on a surface in extremely thin and strongly adherent films, holding the bottles inverted against a support, heating the support so that thereby the bottle neck will be heated, carrying the bottle on the support into and out of the hot melted material whereby expanding

air within the bottle flowing out around the supported edge of the bottle-rim will prevent entrance of liquid-repellant material to the inside of the neck and a very thin film of the liquid-repellant material will be laid on the outside of the bottle-rim and neck, and permitting excess melted material to drain therefrom while the bottle remains supported by said heated surface.

5. A process of preparing bottles so as to render them non-dripping which consists in melting and heating a liquid-repellant material having capability of solidifying on a surface in extremely thin and strongly adherent films, holding the bottles inverted against a support, heating the support so that thereby the bottle neck will be heated, carrying the bottle on the support into and out of the hot melted material whereby expanding air within the bottle flowing out around the supported edge of the bottle-rim will prevent entrance of liquid-repellant material to the inside of the neck and a very thin film of the liquid-repellant material will be laid on the outside only of the bottle-rim and neck, and continuing to support said bottle in an inverted position until excess material has been drained therefrom and the remaining film has cooled and become hard.

6. A process of preparing containers having pouring orifices so as to render them non-dripping which consists in melting and heating paraffin wax of a high melting point for such wax having capability of solidifying on a surface in

extremely thin and strongly adherent films, holding the bottles inverted against a support, heating the support so that thereby the bottle-neck will be heated, and carrying the bottle support into and out of the hot melted material whereby expanding air within the bottle flowing out around the supported edge of the bottle-rim will prevent entrance of liquid-repellant material to the inside of the neck and a very thin film of the liquid-repellant material will be laid on the outside only of the rim and neck. 5 10

7. A process of preparing bottles so as to render them non-dripping which consists in melting and heating paraffin wax of a high melting point for such wax having capability of solidifying on a surface in extremely thin and strongly adherent films, preliminarily heating the neck of the bottle to cause the air in the bottle to expand and be expelled around the mouth of the bottle, inserting the rim of the bottle into said heated wax and retaining it there for a sufficient duration of time to heat it to substantially the temperature of the heated wax, maintaining the temperature of said heated wax constant, and thereafter withdrawing said rim from the heated wax and causing removal of excess wax and cooling, whereby a very thin film of said wax will be laid on the outside only of the bottle-rim and neck. 15 20 25
